MICROPHONE

Lute P. Wassmann, Chicago, Ill., assignor to Electro-Voice, Incorporated, Buchanan, Mich., a corporation of Indiana

Filed Mar. 4, 1963, Ser. No. 73,822

Term of patent 14 years

(Cl. D26—14)

Fig. 1

Fig. 3

I claim:

The ornamental design for a microphone, as shown and described.
